Design No. 12,701, dated January 24, 1882.

UNITED STATES PATENT OFFICE.

WALTER M. CONGER, OF NEWARK, NEW JERSEY.

DESIGN FOR A TEA-TRAY.

SPECIFICATION forming part of Design No. 12,701, dated January 24, 1882.

Application filed June 18, 1881. Term of patent 14 years.

To all whom it may concern:

Be it known that I, WALTER M. CONGER, a citizen of the United States, residing in the city of Newark, county of Essex, and State of New Jersey, have invented certain new and useful Improvements in Designs for Tea-Trays and Waiters, fully described and represented in the following specification and the accompanying photographs, forming a part of the same.

10 The design is shown in the annexed facsimile as photographed directly from a tea-tray of elliptical shape, having a flange turned upwardly and outwardly all around its edge, and as the flange is viewed obliquely in the photograph, the proportions of that part of the design depicted upon the flange are slightly distorted.

15 In the fac-simile the design is presented merely in black and white to secure an effective print, and the bottom of the tray is represented as black, excepting a band of white adjacent to the flange and separated therefrom by a narrow black line or stripe. The flange is represented as white with a black border upon its outer edge, from which it is separated by a narrow scalloped line, and it is decorated by a row of trefoils or clover-leaves, each of which is provided with a short stem projected toward the center of the tray. Upon the flange, 20 midway between each clover-leaf, is shown an arrow-head pointed inward. The white band upon the bottom of the tray is decorated by a series of round spots disposed at equal distances.

35 The above-described design may be composed in practice of any harmonious colors, as it is the shape and not the color which constitutes the design I claim.

40 I have heretofore made the bottom of the tray black, and the flange and band upon the bottom in bronze, the trefoils and round spots green, and the arrow-heads black, and employed red for the scalloped and dividing lines; but any colors may be used to produce an agreeable contrast.

45 The scalloped line and the narrow stripe at the bottom of the flange may be dispensed with, as they are not a material part of my design, the essential features of the same being the trefoils and arrow-heads upon the flange, 50 and the spots of color upon the bottom of the tray adjacent to the trefoils. The number of these may be varied without greatly affecting the beauty of the design; and I may therefore use a greater or lesser number than what are 55 shown in the fac-simile.

Having thus fully described the essential features of my design, I claim—

55 The trefoil design for tea-trays and waiters, substantially as shown and described.

60 In testimony whereof I have hereunto set my hand in the presence of two subscribing witnesses.

WALTER M. CONGER.
